ABSTRACT OF THE DISCLOSURE

A voltage switching device comprising a lower limit voltage switching circuit for cutting off a D.C. load circuit when the applied voltage to the load circuit through said switching circuit has gotten lower than a predetermined voltage and/or an upper limit voltage switching circuit for cutting off the load circuit when the applied voltage has gotten higher than a predetermined voltage; whereby said device supplies power to the load circuit at voltages defined by said predetermined voltages.

The present invention relates to a voltage switching device for automatically interrupting a load circuit by detecting the variation of an input applied voltage when an applied voltage rises or drops over or under a fixed value.

A general object of the invention is to provide a voltage switching device which comprises a signal detection circuit wherein a base of a pre-stage transistor of a trigger circuit employing two transistors is connected to a point between positive and negative input terminals divided by two resistances and a current amplification circuit wherein a collector of a post-stage transistor is connected with a base of a transistor of the type different from said post-stage transistor.

More precisely speaking, the present invention concerns a voltage switching device having a trigger circuit of the modified type formed by inserting resistances between emitter terminals of a direct-coupled amplifier employing two transistors of a different type, the ordinary trigger circuit of said voltage switching device being formed by use of an upper limited voltage switch for automatically interrupting the load circuit in case the input applied voltage from a power source drops under a fixed reference voltage and two similar type transistors, a voltage switching device formed of an upper limited voltage switch for interrupting the load circuit in case the input applied voltage rises over a fixed reference voltage or in combination of said upper limited voltage switch and a lower limited voltage switch, and a voltage gate circuit for charging current to the load only when the input applied voltage remains in a certain range of voltage.

The present invention also includes an automatic voltage switching device for automatically providing a number of batteries required for supplying allowable voltage to the load to make a switching operation applying said upper limited voltage switch to a plurality of batteries arranged in series and variable in voltage and voltage switching device adapted to act at a constant reference voltage irrespective of variation of peripheral temperatures applying temperature compensation to said upper limited voltage switch and said lower limited voltage switch.

The voltage switching device according to this invention is adapted for use to prevent the excessive discharge of a dry battery or the excessive charge of a storage

2

battery, to avoid leaking of liquid due to excessive discharge of the dry battery, protecting the device in use of batteries from damages and eliminating deterioration of characteristics of a battery caused from excessive charge of the storage battery, and also to prevent the occurrence of accidents.

In the conventional direct current circuit having a battery as a power source, drawbacks were found in that excessive discharge of a dry battery caused leakage of liquid and gave no small damage to a device employing batteries. Furthermore, lowering of the power source voltage gave rise to variation in the characteristic of a circuit that has already been provided.

Also in a storage battery of the closed type, frequent occurrence of excessive charge and discharge adversely affected the characteristic of a battery during operation in later stages and occasionally and unexpectedly induced explosion of the battery.

The removal of such drawbacks has, therefore, necessitated the provision of a voltage switch to interrupt the load circuit automatically whenever the voltage rises or drops over or under the reference voltage.

Most of the voltage switches which have been adopted conventionally for the above-mentioned purposes included electromagnetic voltage relays which however brought a great loss of electricity and the undesirable effects of anti-oscillation and wear resistance in addition to a variety of electrical and mechanical troubles such as hysteresis loss and chattering in voltage during the On and Off periods.

Other conventional voltage switches were mostly adapted to perform the switching of a circuit by providing a reference operating voltage by means of a constant-voltage diode (Zener diode). However, the constant-voltage diodes of the same kind could not be easily obtained. Ordinarily, electron avalanche occurred even with the rise or drop of voltage even in 7 to 9 v. and the operating characteristic became worse. It has required several ma. of current for attaining an operating stability so that considerable loss of electricity was not inevitable for the circuit having a power source of limited voltage.

One object of the present invention is, therefore, to provide a voltage switching device which is capable of removing such drawbacks, while ensuring small power loss, good anti-oscillation and wear resistance beside deficiency of hysteresis and chattering.

The nature of the invention will be more clearly understood from a detailed description of preferred embodiments of the invention with reference to the accompanying drawings in which:

FIG. 1 is a circuit diagram of the upper limited voltage switch of an embodiment of this invention;

FIG. 2 shows equivalent circuits of the voltage switch of this invention in the Off condition;

FIG. 3 is a schematic diagram showing the operating characteristic of the voltage switch of this invention;

FIG. 4 shows a variation characteristic of output voltage of a battery when the battery is charged or discharged;

FIG. 5 is a diagram showing comparative lines showing characteristics of the voltage switch of this invention in FIG. 1 and the conventional electromagnetic voltage relay;

FIG. 6 is a circuit diagram of the upper limited voltage switch in another embodiment of this invention;

FIG. 7 is a diagram showing the characteristics of the upper limited voltage switch in FIG. 6 and the voltage switch in FIG. 1;

FIG. 8 shows a circuit of the upper limited voltage switch in another embodiment of this invention;

FIG. 9 is a circuit diagram showing an embodiment of the lower limited voltage switch;

FIG. 10 shows an operating characteristic of the lower limited voltage switch in FIG. 9;

FIG. 11 is a schematic diagram showing an embodiment of the voltage gate circuit according to this invention;

FIG. 12 shows an operating characteristic of the upper limited voltage switch section;

FIG. 13 shows an operating characteristic of the lower limited voltage switch section;

FIG. 14 shows an operating characteristic of the gate circuit of the lower limited voltage switch section in FIG. 13;

FIG. 15 is a circuit diagram showing an embodiment of the automatic voltage switch;

FIG. 16 is a circuit diagram of the lower limited voltage switch section of the device in FIG. 15;

FIG. 17 shows an output characteristic of the device in FIG. 15;

FIG. 18 is a circuit diagram of the automatic voltage switch according to another embodiment of this invention;

FIG. 19 shows an output characteristic of the device shown in FIG. 18;

FIG. 20 is a circuit diagram wherein the upper limited voltage switch has been provided with temperature compensation;

FIG. 21 is a graphical representation of temperature variations of V_{be} of pre-stage transistors of the upper limited voltage switch;

FIG. 22 is a graph showing variations of the operating voltage in response to variation of temperature of the upper limited voltage switch and another switch shown in FIG. 1;

FIG. 23 is a circuit diagram showing another embodiment in which the temperature compensation has been applied to the upper limited voltage switch in FIG. 1.

Referring now to FIG. 1, a preferred embodiment will now be illustrated.

In the figure, Tr_1 denotes an NPN transistor and Tr_2 denotes a PNP transistor. Emitters of both transistors are connected through a resistance R_5 . A base of the transistor Tr_1 is connected to a point of connection between resistances R_1 and R_2 which are connected in parallel to a power source B. The emitter of the transistor Tr_1 is connected to the negative electrode of the battery B through a resistance R_3 and the collector to the positive electrode of the battery B, respectively. The emitter of the transistor Tr_2 is connected to the positive electrode of the battery B through a resistance R_7 and the collector to the negative electrode of the battery B through a resistance R_6 .

Tr_3 denotes an NPN transistor which forms a current amplification circuit, the base of which is connected to the collector of the transistor Tr_2 and the emitter of which is connected to the negative electrode of the battery B, while the collector of which is connected to the positive electrode of the battery B, respectively.

The invention is particularly characterized by the provision of a feed back means connecting through a resistance R_5 of the emitter terminal of a D.C. amplifier in use of transistors Tr_1 and Tr_2 of the different type and a detection means for detecting variation of input voltage by connecting a base of the pre-stage transistor Tr_1 in the point of connection of the resistances R_1 and R_2 which are connected in parallel to the battery B thereby to form a trigger circuit of the modified type. The transistor Tr_3 herein provided is a transistor for amplifying electric current for intermittently flowing a large load current.

In the relationship of the transistors Tr_1 , Tr_2 and Tr_3 , if the transistor Tr_1 is in the On condition, the transistors Tr_2 and Tr_3 will turn On and when the transistor Tr_1 is in the Off condition, the transistors Tr_2 and Tr_3 will turn Off and thereby charging of current to the load is interrupted.

According to the relationship of a base voltage E_{b1} , an emitter voltage E_{e1} and operating voltage V_{be1} of the transistor Tr_1 , the operation of the device in turning from Off to On is accomplished on the condition that the following formula has been established:

$$E_{b1} - E_{e1} \geq V_{be1} \quad (1)$$

An equivalent circuit considering the power source when the device is in the Off condition consists of a closed circuit containing the resistances R_1 and R_2 and a closed circuit containing the resistances R_3 , R_5 and R_7 so that the operation of the device in turning from Off to On is determined only by the aforesaid resistances.

Accordingly, the base voltage E_{b1} is determined by the resistances R_1 and R_2 and also an input voltage E_{in} as follows:

$$E_{b1} = \frac{R_1}{R_1 + R_2} \times E_{in} \quad (2)$$

On the other hand, the emitter voltage E_{e1} is determined by the resistances R_3 , R_5 and R_7 and the input voltage E_{in} as follows:

$$E_{e1} = \frac{R_3}{R_1 + R_2 + R_3} \times E_{in} \quad (3)$$

Therefore, the value E_1 of the input voltage E_{in} when the circuit turns from Off to On is obtained from the Formulas 1 to 3.

There results

$$E_1 = \frac{V_{be1}}{\frac{R_1}{R_1 + R_2} \frac{R_3}{R_3 + R_5 + R_7}} \quad (4)$$

Should the input voltage E_{in} turn E_1 , then

$$E_{b1} - E_{e1} > V_{be1}$$

and the collector current flows in the transistor Tr_2 and the following regenerative action is effected.

Collector current of Tr_2 starts to flow

After $E_{b1} - E_{e1} \geq V_{be1}$ has been attained, the voltage of E_{out} at a point P is impressed on the output by triggering in the period of the input voltage E_1 by said regenerative action as shown in FIG. 3. In the output voltage E_{out} in said period, $V_{ce3}(\text{SAT})$ becomes small since the transistor Tr_3 is in a saturated condition. Then a voltage which is almost equal to the input voltage is applied on the load. Even when the input voltage rises and reaches E_Q , there will be obtained an output voltage of E_{out} proportional to the input voltage since the former is in a stable point of operation.

The operation of the device in turning from On to Off is accomplished when a formula $E_{b1} - E_{e1} - A < V_{be1}$ has been established.

By a regenerative action reverse to the preceding case, the current returns from a point P' to zero. That is to say, the collector current Tr_2 decreases in the following way:

As shown in FIG. 3, the input voltage upon turning from On to Off is E_2 and there is established a relationship of $E_1 > E_2$ which is caused from the backlash effect which is inherent in the switching circuit of a transistor.

The magnitude of this value varies depending on the

loop gain. Therefore, if $A=1$, there would result $E_1=E_2$; if $A<1$, $E_1<E_2$, and if $A>1$, $E_1>E_2$.

Since $A>1$ in the device of this invention, a voltage difference between E_1 and E_2 or the magnitude of the hysteresis value can vary with the change of the aforesaid loop gain A and thereby a desirable circuit can be formed by determining it with the value of the resistance R_5 . When the value of the resistance R_5 is small, the value of hysteresis would be large and when the value of the resistance R_5 is large, the value of hysteresis would be small.

Thus, by connecting the emitters of the transistors Tr_1 and Tr_2 of the different type with each other through the resistance R_5 and connecting the base of the pre-stage transistor Tr_1 to the point of connection of the resistances R_1 and R_2 connected in parallel to the power source B, it is capable of attaining an excellent switching operation so as to be interrupted or saturated with reference to the value of voltage obtained by the Formula 4.

However, it should be noted that, by omission of the resistance R_5 from between the transistors Tr_1 and Tr_2 , the voltage between the base and emitter terminal of the pre-stage transistor Tr_1 will reach an operating voltage V_{be1} and thereby the transistors Tr_1 , Tr_2 and Tr_3 will become conductive. Further, as the input voltage rises and shifts from the unsaturated condition to the saturated condition, the characteristic of the rising operation will become bad, so much so that it became incapable of performing a complete interruption because of the long operating time of the activated region and electron avalanche as seen in the $V_{be}-I_c$ characteristic of the transistor.

One embodiment in which the aforesaid upper limited voltage switch was employed as a means for preventing overdischarge of the dry battery will be presently described.

First, a load was connected between positive and negative terminals for starting discharge. When the voltage reaches a discharge terminating voltage, the load was intercepted and the battery voltage was examined. The result obtained is shown in FIG. 4. If the load is interrupted intentionally upon reaching a terminating voltage a period of time t_1 after the discharge, the output voltage triggers from a point O to the point P instantaneously. If the load is again connected and the discharge is started at the point P, the voltage reaches the discharge terminating voltage again after a period of time t_2 . In this manner, the same operation is repeated several times.

If the device is operated as an upper limited voltage switch for preventing overdischarge of a battery and if a hysteresis value is too small, it often occurs that the voltage of the battery triggers in an instant and the circuit which has once turned Off will turn On again thus causing chattering at the time when the load current is intercepted. Such trigger of voltage of the battery varies with the kind and operation of the battery so that the resistance R_5 may preferably be adjusted to obtain a value of hysteresis fitted to such characteristic as described.

Moreover, the operating voltage of the circuit in the present device is determined in proportion to the dividing ratio of the resistance R_1 and R_2 so that the operating point can easily be provided.

The consuming current upon the circuit being intercepted is the current to be consumed by the resistances R_1 and R_2 and R_3 , R_5 and R_7 , such as shown in the equivalent circuit in FIG. 2, so that by selecting the values of such resistances possibly large in magnitude, it is possible to limit the power loss to a minimum.

For example, a comparison has been made with respect to the operating characteristics of the upper limited voltage switch of cut off voltage 4 v., load current 150 ma. rating according to this invention with the conventional electromagnetic voltage relay. The result is shown in FIG. 5. In carrying out the experiment the

circuit data of the upper limited voltage switch of this invention were defined as follows:

$R_1=10\text{ K}\Omega$, $R_2=39\text{ K}\Omega$, $R_3=510\Omega$, $R_4=22\text{ K}\Omega$
 $R_5=7.5\text{ K}\Omega$, $R_6=2.2\text{ K}\Omega$, $R_7=1\text{ K}\Omega$, $Tr_1=2SC-183$
 $Tr_2=2SB-172$, $Tr_3=2SC-182$

No-load current in the On and Off conditions and the value of hysteresis in the On and Off conditions are shown in the table below. Accordingly, it is seen that the device of the present invention has excellent characteristics.

	On (v.)	Off (v.)	On (ma.)	Off (ma.)	Hyster- esis value
15 Conventional device.....	4	1	23	Off to On 22, On to Off 6.	3
Device of this invention....	4.1	4.0	3.5	0.55.....	0.1

In FIG. 5, the arrow "On" denotes an operating point when the voltage was increased gradually from zero upwards, while the arrow "Off" denotes a non-operating point when the voltage dropped from the On condition. In this instance, H shows a value of hysteresis or the voltage in the On and Off conditions.

25 Next, another embodiment of the upper limited voltage switch is illustrated with reference to FIG. 6.

In the embodiment of FIG. 1, it has been shown that when the input voltage reaches a cut-off voltage, the load circuit is intercepted thereby reducing the load current to zero, and, as in FIG. 2, showing an equivalent circuit in the Off condition, some hundreds of ma. current flow normally due to the resistances R_1 , R_2 and R_3 , R_5 and R_7 thus causing a loss. Further, when the load current is so low as some ma., the leaking of liquid of the battery for preventing the overdischarge is much lessened in effect. Therefore, the embodiment shown in FIG. 6 is intended to minimize the aforementioned loss of current as much as possible. The difference of the embodiment from the one shown in FIG. 1 resides in the position of connection of the transistor Tr_3 for amplifying the current, so that an arrangement was made in the manner that the transistor Tr_3 is connected to the negative input side for the switching operation. Then, if an Off condition has been set up, the power supply for the switching circuit and the load are interrupted and the input current turns zero.

In the preceding arrangement, resistances are provided by insertion between the emitter terminals of the D.C. amplifier employing transistors Tr_1 and Tr_2 of the different type thus to form a different trigger circuit therein. The base of the NPN transistor in the pre-stage is connected to the point of connection between the resistances R_1 and R_2 . Between the resistance R_1 and the negative electrode, there is connected the NPN transistor Tr_3 so that the emitter will come to a side of the negative electrode of the battery B and the collector to a side of the resistance R_1 . The base of the transistor Tr_3 is connected to the collector of the PNP transistor Tr_2 in the post-stage. Herein C denotes a condenser for starting operation and it is provided by insertion between the emitter and collector of the transistor Tr_2 . Said condenser is adapted to enable the input voltage E_{in} to be instantaneously impressed on both ends of the resistances R_1 and R_2 . R_6 is a resistance provided for reducing the current when it is placed between the base and the emitter of the transistor Tr_3 . The load R_L is connected between the positive electrode of the battery B and the collector of the transistor Tr_3 . In the operation of this device, the transistor Tr_3 is used in a state of saturation so that the voltage $V_{ce3}(\text{SAT})$ between the emitter and the collector is extremely small and the power source voltage E_{in} and the voltage impressed on both ends of the resistances R_1 and R_2 are almost equal. Accordingly, the condition of the circuit in the On and Off conditions is entirely the same as in the embodiment shown in FIG. 1,

wherein, if the interpole voltage between the base voltage E_{b1} and emitter voltage E_{e1} of the transistor Tr_1 is higher than the operating voltage V_{be1} in value, the circuit remains in the On condition and, in the reverse case, the circuit will be in the Off condition.

Since the signal applied voltage of the base of the transistor Tr_3 becomes zero when the circuit is in the Off condition, the transistor Tr_3 turns completely Off and the current from the power source turns almost zero leaving only the current for the transistor Tr_3 . At this time the battery B is in a no-load condition so that the battery voltage seems to trigger in an instant and to turn On once again as described about the embodiment in FIG. 1. However, in the present embodiment, the transistors Tr_1 , Tr_2 and Tr_3 are arranged in such a relationship that after Tr_1 and Tr_2 turn On, Tr_3 turns On by a delay phenomenon so that the battery voltage does not turn On again by its trigger.

Now it is to be understood that the circuit just turns from Off to On either when the switch SW is turned from Off to On when the input voltage is larger in value than the voltage as attained by the Formula 4 or when the power source battery is replaced by another power source battery having the switch SW in the On condition. Due to such an operation, there is no chattering when the load current is intercepted irrespective of the magnitude of the value hysteresis.

The condenser C acts for starting the transistors Tr_1 and Tr_2 to turn On by impressing the input voltage E_{in} on both ends of the resistances R_1 and R_2 in an instant when the switch SW is turned from Off to On. After the transistors Tr_1 and Tr_2 turn On, the base of the transistor Tr_3 is impressed with the signal voltage through the collector of the transistor Tr_2 . Then the transistor Tr_3 turns On and the load R_L is impressed with the voltage E_{out} being almost equal to the input voltage.

The operating characteristic of the embodiment will now be illustrated with reference to FIG. 7 in contrast with the one shown in the embodiment of FIG. 1. Here the upper limited voltage switch is shown in solid lines. If the input voltage E_{in} gradually drops and reaches an operating point in the Off condition, the circuit will be completely intercepted. In the arrangement shown in FIG. 1, however, the consuming current due to the resistances R_1 and R_2 and R_3 , R_5 and R_7 flows always in the circuit as shown by dotted lines.

Therefore, the device of this embodiment does not suffer any loss of power in the period of Off condition and no chattering takes place in the cut-off period of load current irrespective of the magnitude of the value of hysteresis.

FIG. 8 shows an embodiment of the upper limited voltage switch which has been somewhat improved over that shown in FIG. 6.

Since, in the embodiment of FIG. 6, a condenser C for starting purpose is connected between the emitter and collector of the transistor Tr_3 , said condenser must have a capacity necessary for flowing the load current in an instant and therefore it is desirable to prefer a larger electrostatic capacity in proportion to the load current.

In comparison, the embodiment in FIG. 8 shows that the position of connection of the condenser C is located between the emitter of the transistor Tr_3 and the base of the transistor Tr_2 with other parts of the construction of which are quite similar to the embodiment of FIG. 6.

Operation of the aforesaid embodiment of FIG. 8 will now be described more in detail. Although in the embodiment shown in FIG. 6 the input voltage E_{in} applied instantaneously between the ends of the resistances R_1 and R_2 and the transistors Tr_1 and Tr_2 become conductive and thereafter the transistor Tr_3 , in FIG. 8, the transistor Tr_2 becomes conductive through the emitter-base of the transistor Tr_2 and further the condenser C instantaneously and, thereby, the transistor Tr_3 becomes conductive in

order to obtain a stable operating condition. At the starting of operation, therefore, it is possible to attain an operating condition by means of the transistors Tr_2 and Tr_3 without relation to the transistor Tr_1 so that the operating time may be shortened. Also, the capacity of the condenser C can be small so as to allow a sufficiently small quantity of current to flow to the base of the transistor Tr_2 and it can be much smaller than that of FIG. 6 in capacity.

In this respect, the device is more economical than that of FIG. 6 in the shorter operating time, much higher stability, and smaller electrostatic capacity for the condenser C.

Illustration will now be made about the lower limited voltage switch for interrupting the load circuit when the input voltage rises over a reference voltage in contrast to the aforesaid upper limited voltage switch for interrupting the load circuit when the input voltage drops below a fixed reference voltage, and also about a voltage gate circuit for supplying a current to the load by combination of the upper limited voltage switch and the lower limited voltage switch only when the input voltage stays in a predetermined range of value.

FIG. 9 shows one embodiment of such lower limited voltage switch as described, in which, R_1 , R_2 - - R_7 denote fixed resistances; Tr_1 and Tr_2 NPN transistors; Tr_3 a PNP transistor; B a power source battery; and R_L a load. A Schmitt circuit is formed of the transistors Tr_1 and Tr_2 of similar type and the resistances R_3 to R_7 . In the dividing point of the resistances R_1 and R_2 which are connected in parallel to a power source B there is formed a detection part for detecting variation of the power source voltage and at the output terminal of said Schmitt circuit there is provided a current amplification circuit formed of the transistor Tr_3 of the type different from the transistors forming the Schmitt circuit. Thus the current flowing to the load R_L which is connected to the output terminal collector of said current amplification circuit and one end of the power source B is intermittently flowed at a value in proximity of a reference voltage as determined by the circuit constant.

The principal operation of the device will follow. When the input voltage E_{in} is lower than said reference voltage, the transistor Tr_1 is in the Off condition and Tr_2 in the On condition and simultaneously Tr_3 turns On, whereby the condition where the output voltage E_{out} which is almost equivalent to the input voltage E_{in} is obtained. Reversely, when the input voltage E_{in} is higher than the reference voltage, the transistor Tr_1 is in the On condition and Tr_2 in the Off condition and the transistor Tr_3 turns Off, whereby the output voltage turns zero.

The performance and the requirements of performance of the device above will more in detail be explained.

In the above embodiment, the reference voltage means the input voltage when the interpole voltage of the base voltage E_{b1} and emitter voltage E_{e1} of the transistor Tr_1 turn to an operating voltage V_{be1} by the formula

$$E_{b1} - E_{e1} = V_{be1}$$

as mentioned above.

Now assume that the input voltage E_{in} is low and it rises gradually from the Off condition of the transistor Tr_1 and the On condition of the transistor Tr_2 and the transistor Tr_1 turns On, then the circuit condition at this time, or when the transistor Tr_1 turns On, is shown by the formula

$$E_{b1} - E_{e1} > V_{be1} \quad (5)$$

Above base voltage E_{b1} when the transistor Tr_1 is in the Off condition is defined by the resistances R_1 and R_2 and the input voltage E_{in} .

Therefore,

$$E_{b1} = \frac{R_1}{R_1 + R_2} \times E_{in} \quad (6)$$

Since the emitter voltage E_{e1} of the transistor Tr_1 depends on the resistances R_6 and R_7 and the emitter base resistance Reb_3 of the transistor Tr_3 and the input voltage E_{in} , it would be

$$E_{e1} = \frac{R_6}{R_6 + \frac{R_7 \times Reb_3}{R_7 + Reb_3}} \times E_{in} \quad (7)$$

Accordingly, the input voltage when the transistor Tr_1 being in the Off condition, turns On and the transistor Tr_2 being in the On condition, turns Off will be as follows from the Formulae 5, 6 and 7:

$$E_1 = \frac{V_{be1}}{\frac{R_1}{R_1 + R_2} - \frac{R_6}{R_6 + \frac{R_7 \times Reb_3}{R_7 + Reb_3}}} \quad (8)$$

Hence the reference voltage E_1 during operation can be obtained.

Examining the performance of each part of the device, it is first found that when the input voltage E_{in} is low, the transistor Tr_1 is in the Off condition and the transistor Tr_2 is in the On condition and the collector-emitter voltage E_{ce2} and operating voltage V_{be2} of the transistor Tr_2 are respectively in saturated states

$(E_{ce2}(SAT) \text{ and } V_{be2}(SAT))$

so that the collector current I_{c2} of the formula flows and stays always at a stable point.

$$I_{c2} = \frac{E_{in} - E_{ce2}(SAT) - E_e}{\frac{R_7 \times Reb_3}{R_7 + Reb_3}} = \frac{(E_{in} - E_{ce2}(SAT) - E_e)(R_7 + Reb_3)}{R_7 \times Reb_3} \quad (9)$$

whereby the output voltage E_{out} is obtained as shown in FIG. 10 and it is impressed on the load R_L .

Next, when the input voltage E_{in} rises and there is established the relationship of Formula 5, the collector current I_{c1} flows out to the transistor Tr_1 . Then by the regenerative cycle shown below, the current returns to zero rapidly from the point P as shown in FIG. 2. The input voltage at this time is E_1 . Thus

From $E_{b1} - E_{e1} > E_{bel}$ I_{c1} flows out
 $\rightarrow E_{b1} - E_{e1} \gg V_{bel} \rightarrow E_{e1} \text{ increases} \rightarrow E_{e1} \text{ drops}$
 $E_e \text{ drops} \leftarrow E_{b2} \text{ drops} \leftarrow$

Reversely, when the input voltage is high and the transistor Tr_1 which is in the On condition turns Off and the transistor Tr_2 which is in the Off condition turns On, the output voltage triggers from zero to the point P' with the input voltage being E_2 as shown in FIG. 10 due to the regenerative performance inversely to the preceding case. This is shown by

$$E_{b1} - E_{e1} - A < V_{bel}$$

(A is a loop gain).

Therefore, a cycle below is obtained.

$\rightarrow E_{b1} - E_{e1} - A \ll V_{bel} \rightarrow I_{c1} \text{ is reduced}$
 $E_e \text{ rises} \leftarrow E_{b2} \text{ rises} \leftarrow E_{e1} \text{ rises} \leftarrow$

There is further a relationship of $E_1 > E_2$ between the operating voltage E_1 in case the input voltage is gradually increased from low to high and the transistor Tr_1 turns On and Tr_2 turns Off, and the operating voltage E_2 , in case the input voltage is gradually decreased from high to low and the transistor Tr_1 turns Off and Tr_2 turns On, said relationship being caused from the backlash effect inherent in the transistor switch circuit. The magnitude

of the value $E_1 - E_2$ in this case varies depending on the aforementioned loop gain A.

Here from

$$\begin{matrix} > & > \\ A = 1, E_1 = E_2 \\ < & < \end{matrix}$$

is obtained, but it is not desirable to make the value of A too small because the characteristic of the rising operation becomes worse.

As described hereinbefore, the lower limited voltage switch of this embodiment has either an interrupted or saturated region at the time of switching operation but has no operating region in the activated region (unsaturated region) so that it can act as a lower limited voltage switch having excellent operating characteristics.

As for example, if said switch may be connected between a storage battery and a charging means, and an operating voltage is provided so that the electric charge to be applied to the storage battery is interrupted by a closing charge voltage, it is quite possible to prevent occurrence of previous accidents due to overcharge of the storage battery.

It is also possible to provide said switch desirably with its operating voltage variable into a dividing ratio of dividing resistances R_1 and R_2 and to make it endurable against oscillation or shock, whereby it is capable of performing a complete interruption because of its non-contact construction. It has advantages of very little chattering and hysteresis at the cut off time of load current and also minimum electric loss.

Now with reference to FIG. 11, the voltage gate circuit will now be illustrated. In FIG. 11, there are provided a section (I) enclosed by chain lines indicating the upper limited voltage switch of FIG. 1 and a section (II) enclosed by chain lines showing the lower limited voltage switch as in FIG. 9. This figure shows that the positive electrode input terminal of the lower limited voltage switch (II) is connected to the upper limited voltage switch (I) in the way that the positive electrode of the lower limited voltage switch (II) is connected to the positive electrode of the lower limited voltage switch (I) and the negative electrode of the lower limited voltage switch (II) is connected to the collector of the transistor Tr_3 .

Quite similar principles and operating characteristics are applied to said upper limited voltage switch (I) and lower limited voltage switch (II) as illustrated in FIGS. 1 and 9 and said principles and characteristics are shown in FIGS. 12 and 13, respectively.

Explaining in detail, the upper limited voltage switch (I) is, if the input voltage E_{in} is higher than E_L the load circuit turns On and a voltage E_{ab} is impressed on the output and if the input voltage is lower than E_L the load circuit turns Off and the output voltage turns zero.

On the other hand, in the lower limited voltage switch (II), if the input voltage E_{ab} is higher than E_H the load current turns Off and the output voltage turns zero, and, if the input voltage E_{ab} is lower than E_H the load circuit turns On and a voltage E_{out} is impressed on the output.

At this time the operating voltage E_L and E_H are represented by the following formulae:

$$E_L = \frac{V_{bel}}{\frac{R_1}{R_1 + R_2} - \frac{R_3}{R_3 + R_5 + R_7}} \quad (10)$$

$$E_H = \frac{V_{bel}}{\frac{R_8}{R_8 + R_9} - \frac{R_{13}}{R_{13} + \frac{R_{14} \times R_{eb6}}{R_{14} + R_{eb6}}}} \quad (11)$$

11

pletely saturated state and $V_{CS}(SAT)$ of the transistor Tr_3 and Tr_6 are very slight.

Therefore,

$$E_{in} \doteq E_{ab} \quad E_{ab} \doteq E_{out}$$

Hence

$$E_{in} \doteq E_{out}$$

Accordingly, if the relationship of the operating voltage E_L of the upper limited voltage switch (I) and the operating voltage E_H of the lower limited voltage switch (II) is assumed $E_L < E_H$, there would be applied a voltage, E_{out} approximate to the input between the output terminals $c-d$ as shown in FIG. 14 on condition that the input voltage is assumed to be

$$E_L \leq E_{in} \leq E_H$$

The voltage gate circuit shown in that embodiment is most advantageously used in some precision electrical machineries such as employing a power source of limited and variable voltage as a battery which is not capable of securing precision of allowance unless the input voltage remains in certain range of voltage.

Said upper limited voltage and lower limited voltage are respectively determined by the dividing ratio of resistances R_1 and R_2 and also the dividing ratio of the resistances R_8 and R_9 so that they can desirably be provided according to necessity.

The following example will give a modified embodiment of the lower limited voltage switch as described in FIG. 9 with respect to an automatic voltage switch. Referring now to FIG. 15, $B_1, B_2 \dots B_n$ denote n power source batteries which are connected in series in sequence. The lower limited voltage switches, $SW_1, SW_2 \dots SW_n$, as shown in FIG. 16, have input terminals $a_1, a_2 \dots$ respectively connected to the positive electrodes of power source batteries $B_1, B_2 \dots$ or contact points $P_1, P_2 \dots P_n$ of the power source batteries. The input terminals $b_1, b_2 \dots$ are connected to the negative electrodes of the power source batteries, respectively.

The output terminals $C_1, C_2 \dots$ of the switches $SW_1, SW_2 \dots SW_n$ are connected by rectifiers $De_1, De_2 \dots De_n$ respectively in the forward direction and connected at a common point, between which and the negative electrode of the power source battery is connected a load R .

Assume now that the operating voltage of the switches $SW_1, SW_2 \dots SW_n$ be E , said operating switch would turn Off if the input voltage of respective switches are higher than E and said operating voltage would turn Off if said input voltages are lower than E so that when the input voltage V_1 of the switch SW_1 , namely, the total voltages of power source batteries in a group assumes $V_1 < E$, the switch SW_1 turns On and the load R is applied a voltage equivalent to V_1 . At this time the input voltages $V_2 \dots V_n$ of the switches $SW_2 \dots SW_n$ are lower than E , the switches $SW_2 \dots SW_n$ turn On and the load R is seemingly impressed with $V_2 \dots V_n$. Since there is established a formula of $V_1 > V_2 > \dots > V_n$ the load current will not flow even if the switches $SW_2 \dots SW_n$ are in the On condition. From the switch SW_1 , however, there is formed, besides the load current, a closed circuit passing through the switches $SW_2 \dots SW_n$ respectively and also through individual battery terminals $P_1-P_2 \dots P_n-P_1$. Therefore, this construction will cause an excessive power loss so that rectifiers $De_1 \dots De_n$ may be connected thereto in order to prevent the flow of current to turn in the reverse direction.

Next, when the input voltage V_1 being impressed on the switch SW_1 becomes $V_1 > E, V_2 \dots V_n < E$ due to change of condition of battery application, the switch SW_1 turns Off and the switches $SW_2 \dots SW_n$ turn On. Then, only V_2 is applied to load R .

A similar procedure is taken when the voltage rises

12

and V_n solely becomes lower than E , wherupon only V_n is impressed on the load R .

One instance is now considered, reverse to the above case, when the voltage of the power source battery gradually drops. Assuming the above relationship being $V_n < E, V_n > E$ initially, only V_n turns On and nothing other than V_n is impressed on the load R . By successive occurrence of voltage drops, the input voltage turns as for example to $V_5 < E, V_6 > E$, then the load R is impressed only by the voltage of V_5 .

Thus, if the voltage drops and turns from $V_1 > E$ to $V_1 < E$ the voltage V_1 is impressed on the load R .

It will, therefore, be appreciated that even if the voltages of the power source batteries $B_1, B_2 \dots B_n$ may vary, an almost constant voltage determined by the operating voltage E of the switches $SW_1, SW_2 \dots SW_n$ is impressed on the load R .

An investigation was made on the relationship of the temperature variation and the terminal voltage V_1 in a fuel cell such as being provided with a plurality of batteries connected in series and have variable terminal voltages with respect to the change of state of application, whereby it was found that the output voltage V_1 has changed greatly with the rise of temperature as indicated by a curve V_1 in FIG. 17. However, the output voltage V_{out} could maintain an almost fixed value by application of the lower limited voltage switch in combination as shown in FIG. 16, although it was subjected to variation within a certain range.

Such a range of variation of the voltage is to be defined by the battery voltage and the number thereof between the switches $SW_1 \sim SW_2, SW_2 \sim SW_3 \dots SW_{n-1} \sim SW_n$, where it is seen that the smaller is the voltage difference between the switches the less the variation of the voltage.

According to the construction of the lower limited voltage switch such as shown in FIG. 16, and the use of a transistor of the lower limited voltage switch and a transistor of the reverse polarity, positions of the connection thereof can be changed corresponding to the variation of the polarity whereby a similar performance as above can be resumed. If it is required, in the lower limited voltage switch, to apply the base current of the transistor Tr_3 with a load current larger than the value multiplied by rate of current amplification, a composite circuit can be constructed in the output stage whereby a circuit may be formed simply to receive any load current.

In such fuel cells as are variable in battery voltage greatly with the change of state of application, the device can well raise the utility of fuels and reduce the operating cost. The present device can also be provided with reserve batteries in series in addition to the required number of batteries for actual use so as to be able to automatically complement the shortage of voltage, which will give another advantage as an accessory of a power source adapted for use in an uninhabited region.

One more embodiment of the automatic voltage switch in use of the lower limited voltage will now be illustrated with reference to FIG. 18.

In FIG. 18, the lower limited voltage switch as shown in FIG. 9 is enclosed by chain lines and it includes an electromagnetic rotary step switch Ry of one circuit multicontact connected between the output terminals $c-d$ of the switch, a fixed terminal N of the switch Ry connected to the positive input terminal a of the lower limited voltage switch and shifting terminals $1 \sim n$ connected respectively to the positive electrodes $P_1, P_2 \dots P_n$ of the batteries $B_1, B_2 \dots B_n$ of the battery group connecting batteries of lower limited voltage in n number sequential series and the negative electrodes of the batteries in the group connected to the negative input terminals of the lower limited voltage switch, wherein the load R_L is connected between the input terminals a and b of the lower limited voltage switching device.

The operation of the aforesaid embodiment is carried out in the way that when the applied voltage between the input terminals *a* and *b* of the lower limited voltage switch is higher than the operating reference voltage *E*, the transistors Tr_2 and Tr_3 are in a non-conductive state and if it is lower than *E*, the transistors Tr_2 and Tr_3 are in a non-conductive state and if it lower than *E*, the transistors Tr_2 and Tr_3 are in a conductive state.

Now assuming that a movable contact piece *N'* having one end connected to a fixed terminal *N* of the rotary step switch *Ry* is connected to a contact point 1, the voltage V_1 of the battery B_1 is impressed between the input terminals *a* and *b* of the lower limited voltage switch. If the voltage V_1 is higher than the operating reference voltage *E* of the lower limited voltage switch, the lower limited voltage switch will be in a non-conductive state, while the contact of the contact piece *N'* and the contact point 1 is maintained unchangeably and the load R_L is impressed by the voltage V_1 .

The input voltage V_1 then drops gradually from this stable operating condition and reaches the operating reference voltage *E*, whereup the lower limited voltage switch assumes a conductive condition and the rotary step switch *Ry* operates. The contact piece *N'* moves to the contact point 2. On the load R_L is impressed the aggregate voltages of the battery B_1 and the battery B_2 . When the contact piece *N'* and the contact point 2 are connected, the applied voltage on the lower limited voltage switch turns V_2 which is higher than the operating reference voltage *E* so that the lower limited voltage switch becomes non-conductive in an instant and the condition of contact of the contact piece *N'* and the contact point 2 is maintained invariably.

In the same manner, if the applied voltage V_2 drops lower than the voltage *E*, the contact piece *N'* shifts to the contact point 3 and similarly the contact piece *N'* shifts one after another from 2 to *n*, whereby the switching operation is started and the load R_L is impressed by a voltage higher than the operating reference voltage *E* of the lower limited voltage switch.

The output characteristic obtained by such an automatic voltage switching device is shown in FIG. 19. Said output voltage, namely, the applied voltage on the load R_L may produce variations within a certain range between maximum and minimum. The minimum is the value of the operating reference voltage *E* of the lower limited voltage switch and the maximum is the value of the reference voltage *E* added by the battery voltage between the movable contact points and said values are determined by the number of batteries between contact points and the voltages of the batteries. It should, however, be noted that the connecting position of the contact points of the electromagnetic rotary step switch can be replaced by the positive input terminal of said lower limited voltage switch and can be connected to the negative input terminal.

As described, the automatic voltage switching device of this embodiment is, in contrast with that of FIG. 15, more desirably be applied to a particular use. It is peculiar advantageous of this device that the contact points are not electrically closed in circuit such as to cause electrical loss and rectifiers are not required for preventing a counter-electric current.

Further embodiment will be shown below, in which said upper limited voltage switch and the lower limited voltage switch are applied temperature compensation so that the load circuit may be interrupted upon reaching a fixed reference voltage even when the peripheral temperature would vary.

With respect to the lower limited voltage switch shown in FIGS. 1, 6 and 8 and also to the lower limited voltage switch shown in FIG. 9, the most important factors of temperature dependency are those of V_{be} , β , and I_{CO} of transistor constants and said factors are collectively dealt with as variations of V_{be} of emitter-base voltage of the transistor in the initial stage.

The temperature dependency of a forward voltage of a junction diode is represented by the following formula wherein temperature coefficients are taken as 2.3 mv/ $^{\circ}$ C. for both germanium and silicon diodes:

$$5 \quad V_{be} = \frac{kT}{q} \ln (1 - \alpha)$$

Where:

k=Boltzmann's constant

T=Absolute temperature

q=Electric charge

The temperature dependency of the transistors is considered quite similar to that of the forward voltage of the junction diode. For example, a graphical representation is given in FIG. 21 with respect to the actual values of a pre-stage transistor used in an embodiment of this invention (FIG. 1). According to this instance, it was found that the value stood at about -2 mv/ $^{\circ}$ C.

In the above upper limited voltage switch and the lower limited voltage switch, the operating condition of the voltage is shown by the formula:

$$V_{be1} = E_{b1} - Ee_1$$

In order to complete the above formula with respect to 25 the variation of V_{be1} due to temperature change, the right side of the equation can be changed, that is to say, either E_{b1} or Ee_1 may be compensated for the temperature change of V_{be1} .

Thus to compensate first E_{b1} , the dividing ratio of the 30 resistances R_1 and R_2 may be made variable in response to the temperature range. This will be accomplished by connection of elements for compensation to the resistances R_1 or R_2 .

In the preceding instance, upon making the temperature 35 compensation by the resistance R_2 , said resistance R_2 must have a positive temperature coefficient and upon making the temperature compensation by the resistance R_1 , said R_1 must have a negative temperature coefficient. Since the resistance element having a negative temperature coefficient such as a thermister can be obtained easily and cheaply compared with that having a positive temperature coefficient, it is more advantageous to use a resistance element such as having a negative temperature coefficient in some portion of the resistance R_1 .

FIG. 20 shows the upper limited voltage switch of FIG. 1 which has been applied the temperature compensation wherein R_1' denotes a resistance element having a negative temperature coefficient as for example a thermister. In comparing the upper limited voltage switch shown in 50 FIG. 20 with the one shown in FIG. 1 with respect to the variation of the operating voltage for the temperature variation, an apparent result has been obtained as in FIG. 22, where, however, the circuit data were rating a 4 v. cutoff, as determined previously in the embodiment of FIG. 1, and the thermister for compensation was computed by experiments.

As shown in the drawings, it may be seen that the 55 variation of the operating voltage generated by changing $\pm 20^{\circ}$ C. with respect to normal temperature 20° C., the variation shown in FIG. 1 is $\pm 6\sim 7\%$, while in FIG. 20 it can be lower than $\pm 1\%$.

Explaining now about the compensation of Ee_1 , it will suffice the purpose by changing the dividing ratio of the resistance R_3 and the resistances R_5 and R_7 with respect 60 to the temperature change, so that the resistance element having the negative temperature coefficient can be inserted in place of the resistance R_5 similarly as in the previous case.

FIG. 23 shows an example of the present embodiment 65 which has been applied to the upper limited voltage switch of FIG. 1.

The temperature compensation can likewise be applied to the upper limited voltage switch in FIG. 8 and also to the lower limited voltage switch in FIG. 9. The resistance element for compensation may even be singly used

15

for the resistances R_1 and R_5 , or other resistances may be applied in connection in series or in parallel whereby the temperature compensation can be modified as required.

Thus the present invention comprises a signal detection circuit formed by connection of a base of a pre-stage transistor of a trigger circuit in use of two transistors to the point between input terminals divided by two resistances and a current amplification circuit formed by connection of a collector of a post-stage transistor with a base of the type different from the poststage transistor characterized by the use of, as main constituents, an upper limited voltage switch wherein transistors of different types are employed for said trigger circuit and resistances are inserted between the emitter terminals of two transistors and a lower limited voltage switch employing an ordinary trigger circuit having transistors of the same type in said trigger circuit. It is advantageous of this invention to be able to present a voltage switching device which is less in power loss, highly resistant to wear and oscillation, and deficient in chattering in hysteresis as well as to offer a voltage gate circuit formed by combination of said upper limited voltage switch and the lower limited voltage switch and an automatic voltage switching device in the use of a lower limited voltage switch.

What we claim is:

1. A lower limit voltage switching device for preventing over discharging of a battery comprising a trigger circuit formed by inserting a resistance between the emitter terminals of direct-coupled amplifiers having an NPN transistor in the prestage thereof and a PNP transistor in the post-stage, the input terminal of said switching device, namely the base of the prestage transistor being connected with the mid-point of the divided resistances between the input and a power source, another NPN transistor with the base thereof being connected with the output terminal of said switching device, namely the collector of the post-stage transistor, the emitter thereof with the negative terminal of said power source, the collector thereof with the negative terminal of said switching device, respectively, and a condenser connected between the base of the post-stage transistor and the emitter of the last stage transistor.

2. An automatic voltage switching device comprising an electromagnetic rotary step switch of one circuit multi-contact type connected to the output terminal of an upper limit voltage switch including a trigger circuit having two NPN transistors the emitters thereof being coupled to each other, the input of said trigger circuit being connected to the mid point of divided resistances between the positive and the negative terminals of a power source, and a current amplification circuit having a PNP transistor being coupled to the output of said trigger circuit, a fixed terminal of said rotary switch connected to a positive input-terminal of said voltage switch, a plurality of movable terminals of said rotary switches respectively connected to the positive electrodes of power source batteries connected in series in a plurality, negative electrodes of a group of power source batteries connected to a negative input terminal of said switch, between which and a fixed terminal of said rotary switch being inserted a load.

3. An automatic voltage switching device as defined in claim 2, wherein the fixed terminal of said rotary switch is connected to the negative terminal of said voltage switch.

16

4. An automatic voltage switching device comprising an electromagnetic rotary step switch of one circuit multicontact type which is connected to the output terminal of an upper limit voltage switch including an automatic voltage switching device comprising an electromagnetic rotary step switch of one circuit multi-contact type connected to the output terminal of an upper limit voltage switch including a trigger circuit having two PNP transistors the emitters thereof being coupled to each other, the input of said trigger circuit being connected to the mid point of divided resistances being the positive and the negative terminals of a power source, and a current amplification circuit having a NPN transistor being coupled to the output of said trigger circuit, a fixed terminal of said rotary switch connected to a positive input terminal of said voltage switch, a plurality of movable terminals of said rotary switches respectively connected to the positive electrodes of power source batteries connected in series in a plurality, negative electrodes of a group of power source batteries connected in series in a plurality, negative electrodes of a group of power source batteries connected to a negative input terminal of said switch, between which and a fixed terminal of said rotary switch being inserted a load, a fixed terminal of said rotary switch connected to a negative input terminal of said voltage switch, movable terminals of said rotary switch connected respectively to the negative electrodes of power source batteries connected in series in a plurality, positive electrodes of a group of power source batteries connected to a positive electrode of an input terminal of said switch, wherein a load is inserted between said switch and a fixed terminal of said rotary switch.

5. An automatic voltage switching device as defined in claim 4, wherein the fixed terminal of said rotary switch is connected to the positive input terminal of said voltage switch.
